HONING MACHINE

Albert M. Johnson, Rockford, Ill., assignor to
 Barnes Drill Company, Rockford, Ill., a corporation of Illinois

Application January 28, 1935, Serial No. 3,714

23 Claims. (Cl. 51—34)

This invention relates to honing machines for producing a very smooth, true finish on the internal cylindrical walls of tubes or cylinders, and has especial reference to an improved machine 5 of this character particularly adapted to operate on the internal surfaces of relatively long tubes disposed in horizontal positions.

The operation of honing the internal cylindrical surface of a tube or cylinder consists generally in simultaneously rotating and reciprocating a honing tool within the same. The nature of this work is such that the reciprocating movement of the tool should be very smooth and with a quick and shockless change of direction at each 10 end of the stroke. Hydraulically actuated means, usually taking the form of a cylinder and piston, have been found to meet these conditions satisfactorily in machines designed to operate on relatively short work pieces. In the case of machines 15 for operating on very long work pieces such as large gun barrels, however, the use of the usual cylinder and piston reciprocating means is impractical because of the large amount of space it requires. With this in view it is one object of 20 the invention to provide a honing machine capable of operating on work pieces of great length which embodies a reciprocating drive means having operating characteristics comparable with those of hydraulic cylinder and piston means but 25 occupying considerably less space.

Another object of the invention is the provision of a novel and efficient means for supporting the spindle carriage upon the ways in a manner which entirely eliminates any possibility of vertical movement of the carriage while offering a minimum amount of frictional resistance to its 30 horizontal movement.

Another object of the invention is the provision of unitary manual controlling means which permits of easy and convenient control of the various 35 operations of the machine.

A further object of the invention is the provision of readily adjustable bearing or sleeve for supporting the honing tool in retracted position 40 and for effectively guiding the tool into and out of the work piece.

Other objects and advantages will be apparent from the following detailed description of a preferred embodiment of the invention illustrated 45 in the accompanying drawings. It is to be understood, however, that many changes in form, construction and arrangement may be made by those skilled in the art without departing from the scope and spirit of the invention as expressed 50 in the appended claims.

Referring to the drawings:

Figure 1 is a front elevational view of a machine embodying the invention.

Fig. 1^a is a side view of the spring plunger mechanism provided for maintaining the reciprocation controlling mechanism in proper position. 5

Fig. 2 is a fragmentary longitudinal sectional view of the machine showing parts of the reciprocating drive mechanism. 10

Fig. 3 is a vertical sectional view taken approximately in the plane of line 3—3 of Fig. 1 and illustrating a portion of the control mechanism.

Fig. 4 is a fragmentary sectional view of the spindle carriage supporting means, the view being 15 taken approximately in the plane of line 4—4 of Fig. 2.

Fig. 5 is a longitudinal sectional view of the tool supporting sleeve and illustrating the tool and a portion of the spindle in retracted position. 20

Fig. 6 is a view, partly in section, taken approximately in the plane of line 6—6 of Fig. 2 and illustrating parts of the spindle carriage reciprocating mechanism.

Fig. 7 is a schematic representation of the various electrical and hydraulic circuits and their relationship with the mechanical operating and control means of the machine. 25

Generally stated, the honing machine as illustrated herein comprises an elongated frame one end of which is provided with a horizontally disposed track or ways upon which a spindle head or carriage is movably supported. Smooth, shockless reciprocating movement is imparted to the spindle carriage by means of cables attached 30 to the carriage and wound in opposite directions on a drum driven through a speed reducing gear train by a reversible fluid motor. As a means of conserving space, the drum is preferably carried in a housing attached to one end of the frame and the fluid motor and driving gears are disposed at one side of the frame adjacent the housing. The driving cables are disposed within the frame 35 and are attached to the underside of the carriage. The latter is effectually supported and guided for horizontal movement by four depending spool shaped rollers. These rollers engage in pairs with the respective members comprising the ways and provide for substantially frictionless horizontal movement of the carriage on the 40 ways. 45

At the end of the frame opposite the drum is provided means for supporting a work piece in operative relation to a tool and spindle carried by the spindle carriage; also a tool supporting 50 55

and guiding sleeve and a coolant directing means. As a further means of conserving space, provision is made for accommodating a coolant settling tank, filter and reservoir or sump within 5 the portion of the frame devoted to supporting the work.

More specifically described, the machine herein disclosed comprises an elongated horizontally disposed frame consisting of a main bed 1 and a 10 work supporting bed 2 which is bolted or otherwise attached to one end of the main bed. The main bed is constructed in the form of a rectangular box-like structure with vertically disposed side walls 3 and end walls 4. Side walls 15 3 terminate at their upper edges in integrally formed inwardly extending flanges 5 (Fig. 4) which serve as protecting shields for certain of the parts and equipment located within the bed. Underlying the flanges of the respective side 20 walls are supported a pair of cylindrical rods 6 extending longitudinally of the bed and forming tracks or ways for a tool spindle head or carriage to be described hereinafter and generally designated by the reference character 7. The 25 rods 6 which are disposed horizontally and parallel to each other are rigidly secured to the spacing blocks 8 which, in turn, are firmly bolted or otherwise attached to the walls 3.

The spindle carriage 7 (Figs. 1 and 2) comprises generally a horizontally disposed base member 9 with depending flanges 10 along each side overhanging the sides 3 of the main bed. At one end of the base member is an upwardly projecting housing 11 within which are enclosed 35 the change speed gears for driving a spindle 12. The spindle 12 is journaled in centrally disposed bearings (not shown) formed on the underside of member 9. The gear housing and rear spindle bearing are closed by a removable cover plate 13 which provides access thereto for the inspection 40 or lubrication of the enclosed parts. A drive shaft 14 for the gear mechanism extends outwardly through a bearing 15 formed on the housing 11 and is connected by a coupling 16 45 with the shaft of an electric motor 17 supported on the member 9. Current is supplied to the motor over conductors forming a flexible cable 18 which is connected to the motor through a rigid arm comprising a bushing 19, elbow 20, conduit 21 and outlet box 22.

The spindle carriage is movably supported on the ways by four spool shaped rollers 23 (Figs. 2 and 4) which are carried by depending studs 24 set in the underside of the base member 9. 55 Each roller consists of a hollow, inverted, generally cone shaped bearing member 25 having a cylindrical depending extension 26 telescoping into the hollow interior portion of a second generally cone shaped bearing member 27. The rollers 23 are supported at their upper and lower ends by conventional anti-friction bearings each comprising a series of steel balls 28. The balls comprising the upper bearing are disposed between an inner ball race 29 which abuts against 60 a shoulder 30 formed on the stud 24 and an outer ball race 31 which abuts against a shoulder formed on the interior surface of the member 25.

The balls comprising the lower bearing are disposed between an inner ball race 32 and an 70 outer ball race 33. The ball race 32 abuts against a supporting ring 33' positioned on the stud 24. The outer ball race 33 is provided with an outwardly extending shoulder which overhangs the lower edge of member 27. A lock nut 34 engaging 75 threads formed on the lower portion of stud

24 maintains the member 27 and its lower bearing in place on the stud and provides for the vertical adjustment of the member for purposes to be described hereinafter. The nut and lower bearing are enclosed by a cup-shaped cover 5 member 35 bolted or otherwise attached to the lower side of member 27. The upper bearings of the rollers are protected by oil retaining rings 36 of conventional design.

The bearing structure, above described, supports the spindle carriage 7 for horizontal reciprocating movement on the ways formed by guide members 6. The weight of the carriage is carried by the members 25 whose downwardly facing inwardly sloping bearing surfaces rest 15 upon the rods 6. Vertical movement of the carriage is prevented by the members 27 whose upwardly facing inwardly sloping bearing surfaces also engage the rods 6. The members 27 are adjusted with respect to members 25 so that a 20 clamping effect is exerted on the guide members. This serves to prevent any vertical movement of the carriage and likewise to center the carriage on the ways. The carriage may be leveled up with respect to the ways by means of shims 37 25 disposed between the stud shoulders 30 and the lower surface of the carriage base member 9.

The motor 17 rotates the tool spindle 12 through the medium of the change speed gear mechanism. This mechanism may be of any 30 suitable type providing a selectively variable gear train whereby the spindle can be rotated at any one of a number of different speeds. The spindle is provided at its free end with a socket for holding a honing tool 38 (Fig. 5) with which 35 the honing operation is performed.

The honing tool 38 shown in Fig. 5, may be of any desired construction and generally comprises a series of elongated circumferentially spaced honing stones 39 arranged in a suitable retaining 40 head 40 provided with interiorly disposed adjusting means permitting expansion and contraction of the stones within a limited range of diameter. To protect the stones from injurious contact with the work piece when the tool is being inserted or 45 removed, the head 40 is also provided with a plurality of circumferentially spaced rigidly secured fiber guide members 41 disposed intermediate the honing stones 39. The honing tool as used in the present construction is provided with 50 a rearwardly extending tubular shank 42 the free end of which is detachably secured in the spindle socket. Knurled gripping members 43 on the shank provide means for setting and locking the stone adjusting means through the medium of 55 mechanism (not shown) disposed within the tubular shank. The shank also carries a serrated fiber supporting ring 44 which serves as a support for the tool in its movement toward and from retracted position, as will be explained here- 60 inafters.

The honing operation, as hereinbefore explained, consists in simultaneously rotating and reciprocating the honing tool in the work piece. Rotation of the tool is effected by the spindle 65 rotating motor 17 and gear train above described. The reciprocating motion is imparted to the tool by reciprocating the spindle carriage and tool supporting spindle. It will be appreciated that in honing a horizontally disposed cylinder, uniform, smooth reciprocation of the tool is necessary to obtain a true surface. Further, the change in direction of motion at each end of the stroke must be effected quickly and without shock so that the surface at these points will receive 75

substantially the same amount of honing as at intermediate points. To this end a novel and effective carriage driving mechanism in the form of a drum and cable arrangement has been provided.

The driving mechanism comprises generally a spirally grooved drum 45 (Figs. 2 and 6) mounted in an enclosing housing 46 and operatively connected to the spindle carriage. The drum is integral with or rigidly supported on a shaft 47 disposed transversely of the main bed 1 the shaft being suitably journaled in bearings 48 in the ends of the housing 46. A spur gear 49, integral with the drum, meshes with a pinion 50 keyed to a shaft 51 extending through an outwardly projecting journal member 52 on the housing into a gear box 53. To the gear box end of the shaft 51 is keyed a worm gear 54 which meshes with a worm 55 keyed to the drive shaft of a rotary fluid motor 56.

The fluid motor 56 may be of any suitable and well known type adapted for quick reversal. The motor is connected to a pressure fluid pump 57 (Figs. 2 and 7) of well known construction through a hydraulic circuit in which a stop valve 58 and a reversing valve 59, to be described later, are interposed. The pressure fluid pump is driven by an electric motor 60 through an over-load release mechanism 61. The fluid motor, pump and driving motor are supported on a sub-base 62 adjacent and, preferably attached to one side of the main bed 1. A surplus fluid sump 63 shown in Fig. 7 may be located within the sub-base.

The above described drive mechanism serves to drive the cable drum 45 in either direction as required and, through its connection with the spindle carriage, to impart reciprocatory movements to the latter. Said connection comprises two flexible cables, 64 and 65, attached to the drum so that when the drum rotates in one direction, one cable is wound up and the other cable is payed out. One end of the cable 64 is anchored to the drum at 66 and the other end is anchored to a lug 67 formed on the underside of the spindle carriage 7 as shown in Fig. 2. One end of cable 65 is anchored to the drum at 68 and the other end, after passing over a sheave 69 is anchored to the lug 67 by means of a threaded rod 70 provided for the purpose of adjusting the tension of the cable. The sheave 69 is provided with a shaft 71 supported in a bearing formed in one end of a lever 72 which is pivoted at 73 on a bracket 74 bolted or otherwise attached to the end wall of main bed 1. Pivotedly attached to the other end of lever 72 is a member 75 extending substantially horizontally through an aperture in the channel member 76 which is rigidly attached to the sides of the main bed. A compression spring 77 bearing at one end upon the inner face of member 76 and at the other end upon a retaining ring 78 secured to member 75 by a nut 79, exerts its force on lever 72 tending to rotate the lever on its pivot and increase the distance between the sheave 69 and drum 45. This serves to take up any slack in cable 65 and maintains the cable under uniform tension. It also provides a cushioning effect which tends to lessen or substantially eliminate any shock incident to the change in the direction of movement of the spindle carriage.

Referring now to Fig. 1, it will be noted that the work supporting bed 2 is offset vertically with respect to the main bed 1. This is to provide sufficient clearance for the tube or cylinder being operated on and permits the machine to be used

when desired on cylinders having relatively large diameters. The upper face of the bed 2 comprises a platen which carries a pair of suitable work holding members 80 which are preferably adjustable to accommodate cylinders of different diameters. To permit the most advantageous positioning of the work holders 80 with respect to the work, the holders are preferably clamped to the platen by means of bolts extending through longitudinally disposed slots therein.

Adjacent the rear end of the bed 2 and attached to the top face thereof is an upwardly extending member 81 formed to receive one end of a cylinder 82 constituting the work piece and to abut against the same in substantially liquid tight contact. A duct 81a (Fig. 1) formed within the member 81 provides a passage through which coolant delivered through the conduit 83 is directed into the cylinder 82.

Adjacent the other end of the bed 2 and centered on the face thereof is an upwardly extending longitudinally disposed U-shaped bracket 84 (Fig. 1) having flanges 85 at each end for attachment to the bed. The upper end of the member 84 is formed to provide ways 86 (Fig. 5) for a tool supporting and guide member 87. The member 87 comprises generally a base portion 88 formed to ride on the ways 86 and having a depending portion overhanging the ways and terminating in teeth constituting a downwardly facing rack 89. The member 87 is also provided with upwardly extending clamping members 90 designed to hold a tool guiding sleeve 91. The sleeve is preferably in the form of a hollow tube having peripheral shoulders 92 designed to fit in the clamping members. One end of the sleeve is beveled so that an inwardly sloping surface is presented to the work piece 82. The sleeve is moved into abutment with and retracted from the work piece by means of a manually operable crank 93 which controls a pinion 94 engaging the rack 89. For locking the sleeve in place, a manually operated locking screw 95 is provided.

It will be further noted that the work supporting bed 2 provides a housing within which the coolant storage and filtering equipment may be conveniently disposed as shown in Fig. 1. The coolant equipment includes a settling tank 96 to which coolant is returned from the work piece through a screened aperture 97 in the face of the bed. Coolant is discharged from the tank 96 onto a removable filter 98 which removes dirt or other foreign matter and permits the coolant to drain into a reservoir or sump 99. A pump 100, driven by an electric motor 101 draws the coolant from the reservoir and delivers it under pressure to the work through the conduit 83 and coolant directing means 81a.

Having in mind the construction of the various working parts of the honing machine above described, the means for controlling the operations of the machine will now be explained. The various manual control members provided for this purpose are grouped for convenient handling at a point near the center of and on the front of the supporting frame as shown in Fig. 1. These include a unitary manually operated means for starting and stopping the spindle driving motor 17 and the fluid motor 56. This control means as shown herein comprises a shaft 102 (Fig. 3) disposed transversely of the axis of the main bed of the machine and journaled in spaced bearing members 103 threaded into opposite ends of a cylindrical passage through a sleeve member 104. The shaft is held in normal position by opposed

compression springs 105 which bear on the inner faces of the respective members 103 and on spaced collars 106 fast on the shaft. Stop collars 107, also fast on the shaft, are adapted to engage the outer faces of the respective members 103 and thereby limit the extent of longitudinal motion of the shaft.

The sleeve member 104 comprises a cylindrical body portion journaled for rotation in a bearing 108 extending through an aperture in and rigidly attached to wall 3 of the main bed 1. The body portion terminates in a flange 109 providing a shoulder which abuts against the outer rim of the bearing. Upon the outer face of the flange 109 is formed an outwardly extending rib 110 which carries a bearing stud 111 in a position substantially perpendicular to the axis of the member 104. The upper portion of the rib 110 defines two upwardly facing, arcuate segments centered on the axis of the stud 111. The rearmost segment is formed on a slightly longer radius than the forward segment and thus presents a shoulder 112 which serves as a stop for limiting the movement of and defining a neutral position for a manual control lever 113.

The control lever 113 (Fig. 3) comprises a base member 114 having a transversely disposed bearing member 115 adapted to receive the bearing stud 111 upon which the lever is enabled to rock in a plane transversely of the longitudinal axis of the machine bed. A depending arm 116 integral with the member 114 defines two cam surfaces adapted to engage spaced stop collars 117 fast on the shaft 102. Carried on the upwardly facing end of the member 114 and offset slightly therefrom is a tubular extension member 118 and a grip member 119. Within these members is disposed a stop pin 120 normally held in engagement with the arcuate segments by a compression spring 121. Manipulation of the grip member 119 relieves the spring tension thus withdrawing the pin 120 and permitting the movement of the control lever past the neutral point defined by the shoulder 112. Thus, when the pin has been withdrawn from its stop position, the lever 113 may be moved toward the right as viewed in Fig. 3, thereby causing the arm 116 to move shaft 102 to the left against the force of the left hand spring 105. Movement of the lever in the opposite direction results in the movement of the shaft 102 to the right, the limit of movement in either direction being governed by the positioning of the stop collars 107. Moreover, lever movement in either direction results in the compression of one or the other of the springs 105 which tends to maintain the shaft 102 in a position corresponding to the neutral position of the lever 113. Accordingly, the lever is automatically returned to neutral position after each operation as soon as the operator releases the same.

The actuation of the control lever 113 as above described reciprocates the shaft 102 and thereby effects the starting and stopping of the spindle driving motor 17. This shaft 102 is operatively attached to an extension member 122 journaled in a bearing 123 which extends through an aperture in and is rigidly attached to the rear wall 3 of the main bed 1. The other end of the extension member 122 is operatively connected with a switch controlling member 125 adapted to actuate switch operating push buttons. In the present instance, the operative connection between the extension member 122 and the member 125 is provided by a peripheral groove 124 in one end of the extension member which engages with

inwardly extending lug carried by the depending arm of the control member. The control member is pivotally supported at 125^a on a bracket 126 carried by the frame of the machine. Reciprocatory movement of the shaft 102 and extension member 122 rocks the control member on the pivot 125^a thereby causing the arm 126^a of the control member to engage one or the other of the switch operating push buttons 127 and 128. When the shaft 102 is shifted to the left as viewed in Fig. 3, the arm 126^a will engage the "start" push button 127. Shifting the shaft 102 to the right brings the arm 126 into engagement with the "stop" push button 128. These push buttons control circuits for the spindle motor 17 as shown diagrammatically in Fig. 7 and accordingly, the motor may be started by moving lever 113 toward the machine and may be stopped by moving the lever away from the machine. As a means of guarding against the accidental starting of the motor, the shoulder 112 prevents the movement of the lever past the neutral position without first releasing the stop pin.

The second controlling function of the control mechanism above described is that of starting and stopping the fluid motor 56. This is accomplished through the medium of a link mechanism shown in Figs. 2, 3, and 7 which is actuated by the rotation of the sleeve member 104 when the lever 113 is rocked in a plane parallel with the longitudinal axis of the machine. This mechanism as shown comprises a link member 129 (Fig. 2) pivotally attached at one end by a pin 130 to an upwardly extending arm 131 integrally formed with a split collar 132 clamped on the sleeve 104. The link is disposed within the main bed 1 of the machine and its other end is pivotally attached to one arm of a bell crank lever 133. The lever 133 is pivotally supported to turn on a vertical axis on a transverse member 134 rigidly supported on the sides of frame 1, and the other arm of the lever is attached to a transversely disposed link 135 (Fig. 7) which actuates the valve 58. The valve 58 which is preferably supported in a housing 136 carried on the frame of the pump 57 consists generally of a cylinder 137 within which a piston 138 reciprocates under control of the mechanism previously described. Pressure fluid is delivered by the pump 57 to the valve through a duct 139 having two branches terminating in ports at each end of the valve. A duct 140 connects the stop valve 58 with the reversing valve 59 and a duct 141 connects the valve with a return duct 142 leading to the sump 63.

To start the fluid motor and, incidentally, the reciprocation of the spindle carriage, control lever 113 is rocked in a counter-clockwise direction as viewed in Fig. 1. Arm 131 follows this movement and shifts link 129 to the left (Fig. 2) and the link, through the medium of the bell crank 133 and link 135, effects the movement of the piston 138 (Fig. 7) to a position in which the ports for the lower branch of fluid pressure duct 139 and the discharge duct 141 are closed. Pressure fluid is accordingly delivered through the duct 140 to reversing valve 59 and thence to the fluid motor. When lever 113 is rocked in a clockwise direction, the motion of the link mechanism is reversed and piston 138 is shifted to a position in which it covers the ports for the upper branch of duct 139 and for duct 140. Pressure fluid is thereby delivered through the lower branch of duct 139 and ducts 141 and 142 to

to the sump 63 and the operation of the motor 56 is stopped.

The two positions of the control lever are defined by a yieldable detent device provided on the sleeve 104. This mechanism as shown herein comprises a ball 143 which together with a compression spring 144 is disposed within a receptacle formed in an outwardly extending projection 145 on the flange 109. The spring urges the ball into depressions 146 provided in the shoulder of the bearing member 108 at the points corresponding to the start and stop position of the lever. This arrangement facilitates the correct positioning of the lever.

Additional manual control elements provided include a start-stop push button switch 147 (Figs. 1 and 7) for controlling the operation of the pump motor 60. This switch is located on the side of the main bed 1 adjacent the control lever 113. Also included is a manual control of the reciprocating movement of the spindle carriage, provided by a lever 148 pivotally mounted on the side of the work supporting bed 2 and connected by a link and removable pin with a stop bar 149 to be described later. Further control of spindle carriage reciprocation is provided by a lever 150 also attached to the stop bar 149 and adapted to rotate the same for purposes to be described hereinafter.

While the reciprocating movement of the spindle carriage may be controlled manually as above stated, it is normally controlled automatically. The mechanism provided for this purpose in the present instance is generally similar to that disclosed in United States Patent No. 1,945,044, granted January 30, 1934, to A. M. Johnson and W. M. Fairbairn and comprises a cam plate 151 (Fig. 7) and link 152 for actuating the reversing valve 59. The cam plate is disposed in a housing 153 supported on a bracket 154 attached to the main bed 1 (Fig. 1). The link extends from the cam plate to the valve 59 which is preferably enclosed in the housing 136 supported on the frame of the pump 57. The cam plate is actuated by the stop bar 149 which is supported on the frame by bearing members 155 and 156, the latter of which is adjustable. The stop bar is provided with a front stop member 157, a rear stop member 158 and a pawl stop member 159, each of which is adjustable with respect to its position on the bar. The front and rear stop members are preferably in the form of disk shaped collars and are adapted to engage a lug 160 depending from the spindle carriage. The pawl stop is designed to operatively engage the lug 160 only when contact is made therewith by the spindle carriage moving toward the retracted positions.

With the spindle carriage in the retracted position shown in Fig. 1 of the drawings, the stop bar 149 will be in its extreme right position and the reversing valve will be set so that the cable drum will be rotated in the proper direction for moving the spindle carriage toward the work. As the carriage moves, lug 160 will pass over the pawl stop without effect and, on reaching a position defined as one limit of the stroke by the member 157, will engage that member and force the stop bar to the left. In this position of the stop bar, the reversing valve will be actuated to reverse the direction of rotation of the cable drum with a consequent reversal of direction of motion of the spindle carriage. When the lug 160 now engages the pawl stop, the stop bar will be forced to the right and the direction of

the movement of the spindle carriage will again be reversed. The function of the pawl stop is to define the limit of the stroke toward the retracted position of the tool, and, once the machine is started, the carriage will be reciprocated within the limits defined by this stop and member 157.

When the honing tool is to be withdrawn from the work, the manually operated control lever 150 is pulled forward, thereby rotating the stop bar and moving the pawl stop 159 out of the path of lug 160. The carriage will then be moved back to its retracted position with the tool entirely withdrawn from the work and resting in the supporting sleeve 87. The release of the lever 150 will permit the stop bar and pawl stop to be moved back into their normal positions under the influence of spring operated plungers 161 which bear against the ends of a cross member 131a fast on the stop bar 149 as shown in Fig. 1a.

It will be noted also, that the manual control lever 148 is adapted for connection to the stop bar by means of a link 148a and pin 148b. This connection is required only when a new work piece is being set up in the machine and enables the operator to manually control the extent of tool movement during the setting up process. During the operating period of the machine, the pin 148b may be withdrawn so that the lever 148 will not be required to follow the movements of the stop bar.

The operation of the reversing valve 59 under control of the stop bar will be most readily seen by referring to Fig. 7 of the drawings. The valve operating link 152 is provided with two piston enlargements 162 and 163 for reciprocation in the valve cylinder. With the stop bar shifted to the left, as shown, the pistons 162 and 163 will define an annular chamber connecting the pressure fluid duct 140 with a duct 164 leading to one side of the motor 56. At the same time, the upper surface of the piston 163 will define a cylindrical chamber connecting a duct 165 leading from the other side of the motor with a discharge duct 165a which is connected to the main discharge duct 142. Pressure fluid supplied to the motor through the hydraulic circuit above described will cause the motor to rotate its shaft in the direction required to drive the spindle carriage to its retracted position.

As the spindle carriage approaches retracted position, the lug 160 will engage the stop member 159 thereby forcing the stop bar and cam plate to the right. Link 152, accordingly, will shift and position the pistons 162 and 163 so that duct 165 will be connected with pressure duct 140 and duct 164 will be connected with discharge duct 142. This will cause motor 56 to rotate its shaft so as to drive the spindle carriage in the opposite direction.

The spindle carriage of the machine disclosed herein is required to operate through a relatively long stroke in operating on long cylinders. Since the spindle driving motor is mounted on the carriage, it too will reciprocate which makes it necessary to provide a very flexible and durable connection over which to supply electric current to the motor. This connection takes the form, in the present instance, of the flexible cable 18 adapted to be wound up on the drum 45 adjacent the cable 64 as the spindle carriage is moved toward the retracted position. The cable 18 is anchored to the drum as at 166 and the three conductors enclosed therein are respectively con-

5 nected with concentrically disposed contact rings 167 (Figs. 2 and 6). The rings are supported coaxially of the drum by an insulating plate 168 (Fig. 6) rigidly attached at one end of the drum. A set of brushes 169 engaging the rings provide electrical contact with the conductors of a feed cable 170 which terminates at the switching contacts to be described hereinafter.

10 The electrical circuits of the spindle motor 17, coolant pump motor 101 and pressure fluid pump motor 60 are shown schematically in Fig. 7 of the drawings. The spindle motor 17 and coolant pump motor 101 are connected in multiple, and 15 the individual conductors extending thereto are connected to respective terminals of the switch 171. The conductors 172 of the incoming power line are connected by branch conductors 173 with corresponding terminals of the switch. A 20 solenoid 174 provided with a series of switch closing members 175 connects the respective conductors when the solenoid is energized. The solenoid is further provided with a switch closing member 176 for completing a locking circuit for 25 itself. The circuit of the solenoid includes a normally open switch 177 closed by a contact member actuated by the push button 127. This circuit also includes a normally closed switch 178 closed by a contact member actuated by push 30 button 128.

Referring back to the description of the manual control mechanism, it will be recalled that the inward and outward movement of the control lever 113 effected the operation of push buttons 35 127 and 128, respectively. The actuation of the push button 127 results in the closure through switch 177 of an energizing circuit for the solenoid 174 which thereupon closes the switches 175 to connect motors 17 and 101 to the power line 40 and switch 176 to complete the solenoid locking circuit. The actuation of button 128 opens the switch 178 to interrupt the solenoid locking circuit and the solenoid becomes deenergized and opens switches 175 and 176. The motors are thus 45 started and stopped under control of the lever 113.

50 The oil pump motor 60 is connected with branch conductors 179 leading to the power line 172 by switches 180 operated under control of a solenoid 181. This solenoid is provided with a circuit similar to that above described for solenoid 174. The circuit is initially closed by a push button operated start switch 182 and the solenoid locks over a circuit including its own switch 55 183. The solenoid is deenergized and the pump motor stopped incident to the opening of push button operated stop switch 184.

60 In operating the machine herein described, the cylinder or tube 82 to be operated on is placed in the work holders and adjusted to the proper position with respect to the tool 38. The tool supporting sleeve 91 is then moved into tight abutment with the work and is clamped in this position by means of the clamp screw 95. After 65 the stop members 157, 158 and 159 have been appropriately positioned on the stop bar, the pressure fluid pump motor 60 is started by the actuation of the start push button 182. The spindle drive motor 17 and coolant pump motor 70 101 are then started by momentarily pushing the manual control lever 113 forward, that is, toward the machine to actuate the push button 127. At the same time, the lever 113 may be rotated in a counter-clockwise direction thereby operating the 75 piston valve 138 to direct pressure fluid to the

fluid motor which thereupon rotates the cable drum in a direction to move the spindle carriage toward the work. As the tool enters the work, the lug 160 on the spindle carriage passes over the pawl stop 159 which then becomes effective 5 to limit the rearward movement of the spindle carriage. The tool is advanced into the work until the lug 160 on the spindle carriage engages the front stop member 157 and shifts the stop rod 149 to the left. The stop rod, through the 10 medium of the cam plate 151 actuates the reversing valve 59 as hereinbefore described, thereby reversing the direction of the fluid motor 56. The fluid motor, accordingly, rotates the cable drum in a direction to move the spindle carriage 15 away from the work. The limit of return movement of the carriage is now defined by the pawl stop 159 which is engaged by the lug 160 on the spindle carriage before the tool 38 is withdrawn from the work. The stop bar is thereby 20 shifted to the right and actuates the reversing valve in the manner hereinbefore described to again effect the movement of the tool into the work. Since the spindle motor 17 is rotating the spindle, the tool is, accordingly, reciprocated 25 and rotated within the tube being worked upon. The honing stones carried by the tool are thus enabled to produce a smooth true surface on the interior of the tube.

When the honing operation is finished, the 30 attendant will cause the honing tool to be withdrawn from the work by pulling the lever 150 forward to move the pawl stop 159 out of the path of the lug 160 on the spindle carriage. The spindle carriage will accordingly return to its 35 retracted position and, when it has reached this position, the attendant will stop further reciprocating movement by rotating lever 113 in a clockwise direction. The actuation of the lever 113 in this manner effects the operation of the 40 stop valve 58 which stops the fluid motor 56 and, incidentally, the carriage driving cable drum. The spindle and coolant pump motors may be stopped at this time by pulling lever 113 forward thereby operating the stop push button 128 which 45 controls the motor circuits. Scratching or otherwise marring the work as the tool is retracted therefrom is prevented by the tool guiding sleeve 91 which maintains the tool in proper alignment with the work. The fiber supporting 50 ring 44, which fits snugly into the sleeve 91 supports the weight of the tool and serves as a guide for the same until the tool is withdrawn sufficiently so that the fiber members 41 engage the wall of the sleeve and take over the support and 55 guidance of the tool.

It will be apparent from the foregoing that the present invention provides a novel arrangement of mechanisms constituting an improved honing machine of minimum dimensions consistent with 60 the character of the tubes or cylinders to be worked on, which is smooth and shockless in operation, is easily and conveniently controlled, and which is efficient in use.

65 I claim as my invention:

1. A honing machine comprising, in combination, an elongated horizontally disposed frame, a carriage mounted on one end of the frame for relative movement longitudinally thereof, a spindle rotatably supported on the carriage, work 70 holding means supported on the other end of said frame for holding the work coaxially with the spindle, a honing tool attached to said spindle and adapted to enter the work, a drum supported at said one end of the frame, a sheave supported 75

- at a point intermediate the two ends of the frame, a cable anchored at one end to said drum and at the other end to said carriage and running over said sheave, a second cable anchored 5 at one end to said drum and at the other end to said carriage, said second cable being wound on the drum in such manner that it is paid out when said first mentioned cable is being wound on the drum, and means for rotating said drum.
- 10 2. A honing machine comprising, in combination, a horizontally disposed frame, work supporting means on one end of the frame, a spindle supporting carriage mounted on the other end of the frame for movement longitudinally there- 15 of, a cable drum supported at one end of the frame, a cable passing over said drum and attached to said carriage, means for rotating said drum to alternately reel up and pay out said cable to reciprocate said carriage on said frame, and 20 yieldable means operatively associated with said cable for absorbing the shock incidental to the reversal of the direction of carriage movement.
3. A honing machine comprising, in combination, a frame, work holding means on one end 25 of said frame, a spindle supporting carriage mounted on the other end of said frame, a cable drum supported at said other end of the frame, a sheave supported intermediate the ends of the frame, a cable connected to said carriage and 30 passing over said sheave and said drum, a second cable connected to said carriage and passing over said drum, said cables being alternately wound up and paid out incidental to the drum rotating in one direction or the other to reciprocate 35 the spindle carriage, and a fluid motor for rotating said drum in either direction.
4. A honing machine comprising, in combination, a frame, a carriage mounted on the frame for relative movement longitudinally thereof, a 40 spindle journaled on the carriage and movable therewith, means at one end of the frame for supporting a tube to be worked on concentrically of the axis of the spindle, a honing tool adapted to enter the tube and having a shank secured 45 to said spindle, means for rotating the spindle, and means for reciprocating the spindle including a cable, a drum for alternately reeling up and paying out the cable, a yieldably supported sheave for taking up the slack in the cable, and 50 means for alternately rotating said drum in opposite directions.
5. A mechanism for reciprocating the tool supporting carriage of a machine tool comprising, in combination, a cable drum, a motor for driving 55 said drum in clockwise or counter-clockwise directions, a cable attached to the carriage and adapted to be wound on the drum incident to its rotation in a clockwise direction and to move the carriage toward said drum, a yieldably supported 60 sheave having its axis parallel with the axis of said drum and spaced therefrom, and a second cable attached to the carriage and passing over said sheave to said drum and adapted to be wound on the drum incident to its rotation in a 65 counter-clockwise direction to move the carriage away from the drum.
6. A mechanism for reciprocating a tool supporting carriage on the bed of a machine tool comprising, in combination, a cable drum sup- 70 ported on one end of the bed, a fluid motor for rotating said drum alternately in clockwise and counter-clockwise direction, a cable attached to the carriage and adapted to be wound on the drum incident to its rotation in a clockwise di- 75 rection to move the carriage toward said drum, a lever pivotally supported intermediate the ends of the bed, a sheave supported on one arm of said lever, a spring member attached to the other arm of the lever and adapted to exert a force tending to move said one arm of the lever 5 and said sheave farther from said drum, and a second cable adjustably attached to the carriage, passing over said sheave and adapted to be wound on said drum incident to its rotation in a counter-clockwise direction to move the carriage toward said sheave.
7. A mechanism for reciprocating the tool supporting carriage on the bed of a honing machine comprising, in combination, cables attached to the carriage, a drum adapted to alternately wind up 15 one of the cables and unwind the other of the cables, a reversible rotary fluid motor drivingly connected to said drum, a pressure fluid pump for supplying pressure fluid to said motor, a valve interposed between said pump and said motor for 20 regulating the delivery of pressure fluid to the motor to control its direction of rotation, and carriage actuated means for controlling said valve.
8. A honing machine comprising, in combina- 25 tion, an elongated frame, a carriage mounted on said frame for relative movement longitudinally thereof, a spindle journaled on said carriage and movable therewith, a motor supported on said carriage and having a driving connection with 30 said spindle, means at one end of the frame for supporting a piece of work to be operated on, a honing tool adapted to enter the work on said supporting means and having a shank secured to said spindle, means for reciprocating the carriage 35 including a cable drum rotated alternately in clockwise and counter-clockwise directions, a current supplying cable comprising electrical conductors connected to said motor and adapted to be wound on the cable drum incident to its rotation in the direction for moving the carriage toward the drum, a plurality of annular members terminating the conductors of said cable and supported on one end of the drum concentrically with the axis of the drum, and means for connecting said conductors with a source of current including a plurality of stationarily supported brushes engaging said annular members.
9. In a honing machine, the combination of a reciprocating carriage, a tool supporting spindle 40 rotatably mounted on said carriage, means for supporting work in position for operation thereon by the tool, a tool supporting and guiding member having an opening adapted to receive the tool, means providing ways for supporting said guiding member, means for moving said member toward and from said work including a manually rotatable pinion journaled on said ways and a rack formed on the member, and manually operable means on said member for preventing movement thereof.
10. In a honing machine, the combination of a reciprocating carriage, a tool supporting spindle 45 rotatably mounted on said carriage and movable therewith, means for supporting work in position for operation thereon by the tool, a member having an opening adapted to receive and support the tool adjacent the work and to guide the same into the work, means supporting said member for movement longitudinally of said spindle, means for moving said member into abutment with the 50 work including the pinion journaled in said supporting means and a rack carried by the member, and means for locking said member in position to prevent its movement away from the work.
11. In a honing machine, the combination of a 55

bed, a carriage mounted on the bed for movement longitudinally thereof, a motor for reciprocating said carriage, a tool supporting spindle journaled on said carriage and movable therewith, 5 a motor for rotating said spindle, a manual control lever supported on said bed for movement in two planes relative to the axis of the bed, means actuated responsive to the movement of said lever through an arc in a plane parallel to the axis of 10 the bed for controlling the operation of said carriage reciprocating motor, and means actuated in response to the movement of said lever through an arc in a plane perpendicular to the axis of the bed for controlling said spindle rotating motor.

12. In a honing machine, the combination of a frame, a carriage mounted on said frame for reciprocating movement thereon, a rotatable tool supporting spindle journaled on said carriage, a manual control lever supported on said frame for movement in two intersecting planes, means actuated 15 in response to the movement of said lever through an arc in one plane for controlling the rotation of said tool supporting spindle, and means actuated in response to the movement of said lever through an arc in the other plane for controlling the reciprocation of said carriage.

13. A manual controlling mechanism for a machine tool comprising, in combination, a sleeve rotatably mounted on the frame of the tool, a shaft extending through said sleeve transversely of the frame, means in said sleeve tending to maintain said shaft in an intermediate position in the sleeve, a lever supported on said sleeve for movement in a plane perpendicular to the axis of the sleeve to rotate the sleeve and for movement in a plane parallel to the axis of the sleeve to reciprocate said shaft against the action of said maintaining means, and machine controlling means actuated in response to the movements of said sleeve and said shaft.

14. A manual controlling mechanism for a machine tool comprising, in combination, a sleeve rotatably supported on the frame of the tool, a shaft extending through said sleeve and supported for reciprocation therein, a manual control lever mounted on said sleeve for rotating the sleeve and reciprocating said shaft, and machine controlling means independently actuated by said sleeve and said shaft incidental to the rotation and reciprocation thereof, respectively, said controlling means including a first electrical switch actuated in response to the movement of the shaft in one direction, a second electrical switch actuated in response to the movement of the shaft in the other direction and valve mechanism actuated in response to the rotation of said sleeve.

15. A manual control mechanism for a machine tool comprising, in combination, a tubular sleeve rotatably supported on the frame of the machine, an outwardly extending projection on one end of said sleeve, a collar having an upwardly extending arm rigidly clamped on the other end of the sleeve, a valve controlling link pivoted on said arm, a shaft extending through the sleeve and having opposed spring members engaging spaced collars on the sleeve for positioning the shaft transversely with respect to the sleeve, spaced collars fast on the outer end of said shaft, a switch controlling member engaged by the other end of said shaft, a manual control lever supported on a bearing carried by said projection on the sleeve, said bearing being disposed eccentrically with respect to the axis of the sleeve to provide leverage for the rotation

of the sleeve incident to the movement of the lever in a plane transversely of the axis of the sleeve, and an arm projecting downwardly from said lever between the spaced collars on the outer end of the shaft, operative responsive to the movement of the lever on its supporting bearing for reciprocating the shaft in opposition to the force exerted by said spring members.

16. In a honing machine, in combination, a frame, a tool spindle carriage movably supported on said frame, and means for rapidly reciprocating said carriage with substantially instantaneous, shockless reversal at each end of its stroke, said means comprising a rotary fluid motor, a quick reverse valve mechanism controlling the operation of the motor, a cable drum driven by the motor, a flexible cable connecting the drum and the carriage, and means controlled by the carriage for operating said valve mechanism.

17. In a honing machine, in combination, a frame, ways carried by the frame, a tool spindle carriage supported for reciprocation on said ways, and means for rapidly reciprocating said carriage on said ways with substantially instantaneous, shockless reversal at the end of each of its strokes, said means comprising a fluid motor, a pressure fluid pump, and an electric motor for driving the pump, a quick reverse valve mechanism interposed between the pump and the fluid motor for controlling the direction of rotation of the motor, a rotary element driven alternately in opposite directions by the fluid motor, flexible driving means operatively connecting said element with the spindle carriage, and means controlled by the spindle carriage for actuating said valve mechanism.

18. In a honing machine, in combination, a reciprocating carriage, a spindle journaled at one end on said carriage and carrying a honing tool at its other end, means for supporting work to be operated on by said tool, means for reciprocating said carriage to advance the tool into operative engagement with the work and to withdraw the tool from the work, and means for supporting the tool in withdrawn position and for guiding the tool into the work, said tool supporting means including an elongated member disposed substantially parallel to the axis of the tool spindle adjacent the tool supporting end thereof, means supporting said member for endwise movement relative to the spindle, manually operable means for moving said member in either direction to adjust its position relative to the work, and means for locking the member in adjusted position.

19. In a machine for dressing cylindrical surfaces, in combination, a frame, a cylindrical abrasive tool, a support on said frame for said tool, a support on said frame for work to be operated on by said tool, a cable drum supported at one end of the frame, a sheave supported on said frame at a point spaced substantially from said one end thereof, a cable connected to one of said supports and passing over said sheave and said drum, a second cable connected to said one support and passing over said drum, said cables being alternately wound up and paid out incidental to the drum rotating in one direction or the other to reciprocate said one support relative to the other support, and a fluid motor for rotating said drum in either direction.

20. In a machine for dressing cylindrical surfaces, in combination, a cylindrical abrasive tool, a support on said frame for said tool, a support on said frame for work to be operated on by said

- tool, and means for reciprocating one of said supports relative to the other support with substantially shockless reversal at each end of its stroke, said means comprising a rotary fluid motor, a quick reverse valve mechanism controlling the operation of the motor, a cable drum driven by the motor, a flexible cable connecting the drum and the reciprocating support, and means controlled by the reciprocating support for operating said valve mechanism.
21. A mechanism for effecting relative reciprocatory movement between the work support and the tool support of a machine for dressing cylindrical surfaces comprising, in combination, cables attached to one of said supports, a drum adapted to alternately wind up one of the cables and unwind the other cable, a reversible rotary fluid motor drivingly connected to said drum, a pressure fluid pump for supplying pressure fluid to said motor, a valve interposed between said pump and said motor for regulating the delivery of pressure fluid to the motor to control its direction of rotation, and control means actuated by the reciprocating support for controlling said valve.
22. The combination in a machine tool having a work support and a tool support, of means for reciprocating one of said supports relative to the other support with substantially instantaneous, shockless reversal at the end of each stroke comprising, a cable drum, driving means including quick reversing means for rotating said drum first in one direction and then in the other direction, cables connected to opposite sides of the recipro-
- cating support and extending to said drum, said cables being pulled alternately in opposite directions in response to the rotations of said drum, and means included in said mechanism for cushioning the shock incident to the reversal of the direction of rotation of said drum.
23. In a honing machine, the combination of an elongated frame, a carriage mounted on said frame for movement longitudinally thereof, a spindle journaled at one end on said carriage and movable therewith, a honing tool secured to the other end of said spindle, supporting means for holding work to be operated on by said tool, means for reciprocating said carriage to traverse the tool across the work, a spindle driving motor on said carriage for rotating the spindle and tool to cause the tool to operate on the work, and means for supplying operating current to said motor while said carriage is reciprocating comprising a current supply cable including a plurality of electrical conductors connected to said motor, a cable drum supported at one end of said frame adapted to be rotated in opposite directions for winding up and paying out said cable to maintain the cable taut while the carriage is reciprocating, a plurality of contact members, one for each conductor of said cable, said contact members being supported at one end of said drum for rotation therewith, and means for connecting said contact members with a source of current including a plurality of stationarily supported contact engaging elements adapted to engage the respective contact members.

ALBERT M. JOHNSON.
